UNITED STATES PATENT OFFICE.

CHARLES E. WHITCOMB, OF NEW YORK, N. Y.

NAME PLATE

Application filed October 14, 1925. Serial No. 62,426.

This invention relates to name plates and more particularly to devices for displaying names or useful indications relating to mail boxes, electric bells, and so forth, for the information of the user.

The primary object of this invention is to provide a neat and efficient device for displaying names or other information adapted for use in various forms in connection with apartment house directories, push button plates, mail boxes, multiple push button plates for desks and other purposes; the main feature of this device being the use of a plate made of transparent material such as glass, said plate being rendered opaque all over except at such places where the names or other indications should be exposed to view.

Another object of this invention is to provide a push button plate of a novel and improved construction, the chief characteristics of which are a neat and attractive appearance, perfect protection from dust of the cards bearing names and other indications and the possibility of keeping the device clean at all times with but little effort.

Other objects and advantages of the present invention will more fully appear as the description proceeds and will be set forth and claimed in the appended claims.

Devices now in use for the display of names in connection with building directories, mail boxes and the like, usually consist of a panel having spaces through which the names or other indications may show through. These spaces are sometimes open, and in this case the dust has free access to the name plates, the appearance of which will in no time become marred, or else the spaces are closed by means of a transparent panel such as glass, and this calls for complicated and expensive arrangements to maintain the transparent panels in place, and also produces finished devices, the outer surface of which is usually irregular and uneven.

This again gives a chance for dust to collect along edges and recesses and makes it necessary to devote quite some time to frequent cleanings of the plate. This operation is further complicated by the necessity of using different cleaning materials for the metal part of the plate and the glass or other transparent material used. Provisions must

also be made, of course, for the easy replacement or removal of the cards bearing names or other indications, so that the finished article as a rule becomes composed of quite a number of different parts, to the detriment of its appearance and of its cost of production.

In my improved device, the front part is a solid plate of transparent material, preferably glass, presenting a smooth and practically unbroken surface which is easy to clean and to keep clean and which moreover partakes of the attractiveness peculiar to this kind of material. A glass surface is superior in appearance to an ordinary metal surface and is to be preferred in most cases; it is smooth and shining but not offensively so, and furthermore, it is impervious to the elements, which on the other hand generally cause a metal plate to tarnish, or to become altered to a more or less degree.

A glass plate thus mounted without a frame is therefore both sanitary and attractive and is furthermore peculiarly adapted for use in a name plate because it is not attacked by any one of the materials in ordinary use for cleaning surfaces, it is fireproof and it has excellent insulating properties. The latter feature is especially important when the name plate is used in conjunction with an electric bell or lighting circuit because no danger may ensue from electric sparks or short circuits.

A glass or transparent front is generally mounted on a backing made of metal or other suitable material having suitable means for the ready insertion or removal of cards bearing names or other indications as may be needed. Both the front plate and the backing may have openings at suitable places for the passage of push buttons when electric bells are used in connection with the name plates.

A few typical embodiments of my invention are illustrated in the drawings in which—

Fig. 1 is a front view in elevation of a push button plate adapted for use as an apartment house directory or for other purposes;

Fig. 2 is a rear view in perspective of the same with the front part partly open to illustrate its construction;

Fig. 3 is a similar view in perspective of

a similar device mounted on a plate of slate or marble or other suitable material already prepared for the mounting of the bell connections, corresponding to the various push buttons;

Fig. 4 is a detail side sectional view in elevation in an enlarged scale, showing the construction of the device of Fig. 3;

Fig. 5 is a front view in elevation of a single name push button plate adapted for individual apartment or house use;

Fig. 6 is a front view in elevation of a push button plate for elevator purposes;

Fig. 7 is a front view in elevation of a push button plate in combination with a house telephone;

Fig. 8 is a front view in elevation of a push button plate adapted for mounting on a disk; and

Fig. 9 is a front view in elevation of a locked multiple mail box also embodying my invention.

Referring to the devices illustrated in Fig. 1 and Fig. 2, it will be observed that the same is composed of a supporting frame 10, to which a metal plate 11 is attached by means of hinges 12, 13. Said plate 11 constitutes the backing and support for the front plate 14, which is made of glass, secured to plate 11 by means of screws 15.

The object of the glass plate is, of course, to permit names and other indications carried by the device, such as 16, 17, to show through. In the case illustrated, the device has a capacity for ten names as at 16, corresponding to ten different apartments as per indications 17, and these indications are caused to show through owing to the fact that the glass plate is rendered opaque all over except at points corresponding to the cards bearing the indications where it is transparent.

It is, of course, possible to directly manufacture such a plate by having it tinted where it should be opaque and clear where it should be transparent, but the cost of production of such an article would be prohibitive; therefore, I prefer to use a plate which is usually entirely transparent and to render it opaque all over except at such points where its transparency is needed.

This result may be obtained in various ways; for instance, the rear surface of the plate may be painted black or some other color all over except at such points where the indications must show through; or else the plate may be mirrored leaving the transparent spaces blank, thus providing a different effect; or else a thin sheet of paper or other material having openings corresponding to the indications to be furnished by the plate, may be attached to the back of the plate or may be interposed between the plate and its support.

These various arrangements may be un-

derstood by referring to Fig. 4 where 14 is the glass plate, 11 is the metal plate on which the same is mounted, and 18 represents a thin layer of opaque material interposed between plate 14 and plate 11, said opaque material leaving uncovered the spaces such as 16 through which the transparency of the glass must be maintained. As stated, 18 may be understood to represent a layer of coloring matter spread upon the rear surface of glass 14, or a mirroring composition, or else a sheet of paper or other material. This layer of opaque matter may also be omitted if desired, and in this case the cards bearing indications will appear against the backing of the metal plate 11. The visibility is still quite as high as before but the appearance which may be obtained by interposing an opaque layer such as 18 between the glass plate and the metal plate is by far superior, because a great variety of neat effects may be obtained by using different colors or other finishes, providing thus a new article of decoration.

It is also possible, of course, to paint various designs in various colors on a sheet 18, if still different effects should be desired; in fact, the decorative possibilities of such an arrangement are well nigh unlimited.

A glass plate constituting the covering of the device is, of course, permanently smooth and easy to keep in a clean and sanitary condition. Suitable provisions for the insertion and removal of cards bearing the necessary indications are provided in connection with plate 11, and a simple arrangement to this end is illustrated in Figs. 2, 4. In the same way it is seen that said plate is provided with openings 19, at such points where cards such as 20 are to be inserted. The upper and lower edges 21, 22, of said openings are offset towards the rear and inwardly so that when plates 11, 14 are connected together, cards 20 can be inserted sidewise between said edges 21, 22, and the rear surface of the glass plate or of opaque layer 18. This provides an arrangement which is both simple and effective and which may be produced at relatively small cost. Plate 11 being hinged to frame 10 which is mounted upon the wall, it is easy to open said plate 11 at any time as shown in Fig. 2, for the purpose of changing or inserting cards.

The device illustrated, also includes push buttons, one for each apartment, as at 23. In the construction shown, each push button comprises a body 23' and an enlarged disc portion 23'' at the rear and the body part is inserted from the rear through suitable openings 24 provided through plates 11, 14. The length of body part 23' is such that the bottom will only project very slightly through the front of the plate, or else will just about reach the front of the plate 14 as shown. In this manner it will be possible

to clean the plate without encountering any obstruction and without causing any of the bells to ring.

In the construction shown in Fig. 3 and Fig. 4, plate 11 is not mounted on a frame such as 10, but is mounted on a board 25, which is already provided with the necessary means for attaching the lines leading to the various bells, so that the device becomes a complete name plate and push button plate in one. The proper connections may be made through plate 25, in any suitable manner for instance by passing one set of wires through central groove 26 and another set of wires through lateral grooves 27, 28 meeting at 29. For each button there is a branch groove such as 30 extending outwardly from groove 26 and a branch groove such as 31 extending inwardly from groove 27 or 28, said grooves leading respectively to terminals 32, 33, to which are connected spring contacts 34, 35, behind each button, in the manner clearly illustrated in Fig. 4.

This construction of spring contacts for an electric bell push button merely duplicates the one now generally in use; but the novel point of the arrangement consists in providing a name plate and a push button plate complete ready for mounting and for connection. This is of itself a new article of manufacture independently of the manner of construction of the name plate itself.

The nature of my invention is thus fairly understood. The remaining figures illustrate various possible applications of my invention in order to furnish an idea of its many possibilities. In Fig. 5, for instance, 36 designates a push button plate comprising name plate 37 and push button 38, adapted for individual use; Fig. 6 represents a push button plate 39 for an elevator signal, bearing indications of up and down 40, 41 and corresponding push buttons 42, 43. Fig. 7 represents a name and push button plate 44, bearing a plurality of name plates 45 and corresponding push buttons 46, combined with a house telephone transmitter 47. Fig. 8 represents a push button plate adapted for use on an executive's desk, where 48 is the plate proper, 49 are name cards, 50 are push buttons corresponding to said name cards and 51 is a card bearing various indications relating to signals. Fig. 9 represents a locked twin mail box, where 52 is the box proper, normally closed by bar lock 53 and 54, 55 are two doors giving access to the inside of the box, said doors having a front glass plate through which name cards 56, 57 show through, in the manner described above.

My invention, is of course, susceptible of many other applications which are not illustrated, all its embodiments including a partly transparent and partly opaque panel extending over the entire front of the device

and possessing therefore the decorative and sanitary possibilities outlined.

However, it is obvious that when a front panel which is or has been rendered partly opaque or partly transparent is used, names and other indications may be painted or attached directly upon the rear surface of the panel in correspondence with the transparent portions thereof. In this case the transparent panel may be mounted directly upon the wall or upon a supporting frame such as 10 and the use of a backing member 11 may be omitted.

The various details of construction may be different from those shown, it being understood that the drawings are intended for illustrative purposes only and not in a limiting sense; I therefore reserve myself the right to carry my invention into practice in any way or manner which may enter fairly into the scope of the appended claims.

I claim:

1. A name plate having a glass outer surface comprising a backing member having means for holding name cards and a glass front panel therefor attached directly thereto, the rear surface of said panel being spread with an opaque layer of paint, leaving blank spaces at points where said name cards may show through.

2. A name plate having a glass outer surface comprising a supporting member, a backing member hinged to said supporting member having means for holding name cards and a glass front panel attached directly to said backing member, said panel having been rendered opaque all over except at points where said name cards show through.

3. A name plate having a glass outer surface comprising a backing member having means for holding name cards, a glass front panel therefor attached directly thereto, said panel having been rendered opaque all over except at points where said name cards may show through, and push buttons projecting through said panel in correspondence of said transparent spaces.

4. A name plate having a glass outer surface comprising a backing member having means for holding name cards, a glass front panel therefor attached directly thereto, said panel having been rendered opaque all over except at points where said name cards may show through, and push buttons projecting through said panel in correspondence of said transparent spaces, said push buttons being substantially non projecting from the surface of said panel.

5. A name plate having a glass outer surface comprising a board, electric bell contact devices mounted on said board, a backing member hinged onto said board and having means for holding name cards, a glass front panel attached directly onto said

- 4. backing member, said panel having been rendered opaque all over except at points where said name cards may show through, and push buttons projecting through said
  - 5. backing member and panel adapted to control said contact devices.
6. A name plate having a glass outer surface comprising a board, electric bell contact devices mounted on said board, a backing member hinged onto said board and having means for holding name cards, a glass front

panel attached directly onto said backing member, the rear surface of said panel having been rendered opaque by a layer of paint, except at points where said name cards may show through, and push buttons projecting through said backing member and panel adapted to control said contact devices, said push buttons being substantially non projecting from the surface of 20 said panel.

CHAS. E. WHITCOMB.
